CLAIM

The ornamental design for a bridge for a pool cue, as shown and described.

DESCRIPTION

FIG. 1 is a front perspective view of a bridge for a pool cue, showing my new design.

FIG. 2 is a left side view thereof.

FIG. 3 is a right-side view thereof.

FIG. 4 is a front view thereof.

FIG. 5 is a rear view thereof.

FIG. 6 is a top view thereof; and,

FIG. 7 is a bottom view thereof.

The broken line areas show portions of the bridge for a pool cue that form no part of the claimed design.

1 Claim, 6 Drawing Sheets
